United States Patent

Des. 238,835

Patented Feb. 17, 1976

238,835

ARMCHAIR

Cesare Cassina, Carimate, Italy, assignor to
Centro Cassina S.r.l., Milan, Italy

Filed Feb. 4, 1974, Ser. No. 439,363

Claims priority, application Italy Aug. 3, 1973

Term of patent 7 years

Int. Cl. D6—01

U.S. Cl. D6—26

FIG. 1

FIG. 2

FIG. 3

FIG. 4

FIG. 5

FIG. 6

FIG. 1 is a front elevational view of the armchair of my new design;

FIG. 2 is a rear elevational view thereof;

FIG. 3 is a top plan view thereof;

FIG. 4 is a bottom plan view thereof;

FIG. 5 is a side elevational view; and

FIG. 6 is a vertical sectional view thereof.

The side not shown in FIG. 5 is a mirror image of the side shown.

I claim:

The ornamental design of an armchair, as shown and described.
